UNITED STATES PATENT OFFICE.

MARY E. VERDIER, OF ALLENTOWN, PENNSYLVANIA.

VIOLIN-BOW.

SPECIFICATION forming part of Letters Patent No. 739,459, dated September 22, 1903.

Application filed September 11, 1902. Serial No. 122,916. (No model.)

To all whom it may concern:

Be it known that I, MARY E. VERDIER, a citizen of the United States, residing at Allentown, in the county of Lehigh and State of Pennsylvania, have invented certain new and useful Improvements in Violin-Bows, of which the following is a full and complete specification, such as will enable those skilled in the art to which it appertains to make and use the same.

The object of this invention is to provide an improved violin-bow which may be conveniently taken apart, so that it may be compactly folded or carried in a small space in a trunk, valise, or other receptacle; and with these and other objects in view the invention consists in a violin-bow constructed as hereinafter described and claimed.

The invention is fully disclosed in the following specification, of which the accompanying drawings form a part, in which the separate parts of my improvement are designated by suitable reference characters in each of the views, and in which—

25 Figure 1 is a side view of a violin-bow made according to my invention; Fig. 2, a longitudinal sectional side view thereof; Fig. 3, a bottom plan view of a part of the frog, taken on the line 3 3 of Fig. 2; Fig. 4, a longitudinal section of a portion of the bow at right angles to the section shown in Fig. 2, and Fig. 5 a section on the line 5 5 of Figs. 1 and 2.

In the drawings forming part of this specification I have shown a violin-bow comprising a staff *a*, having a handle *a*² at one end, with which is connected the frog *c*. The staff *a* is divided at *a*³ into separate parts *a*⁴ and *a*⁵. One of these parts is provided with a sleeve *b* and the other with a reduced member *b*², with which is connected a thimble *b*³, which is adapted to closely fit within the sleeve *b*, and this thimble is provided with a transverse projecting portion *b*⁴, adapted to enter corresponding recess *b*⁵ in the end of the part *a*⁴ of the staff of the bow, the object of this construction being to prevent the part *a*⁵ of the staff from turning in the sleeve *b*.

The frog *c* is composed of two parts *c*² and *c*³, and the part *c*² is mounted on the side of the handle *a*² in the usual manner and is provided with a block *c*⁴, which moves in a recess *c*⁵, formed in the handle *a*², and movable

or turnable in said handle *a*² is a screw *d*, which passes through said block, as shown at *d*², and the screw *d* is provided with a head 55 or handle *d*³, and by turning said screw the frog may be moved longitudinally of the handle *a*² in the usual manner, as will be readily understood.

The part *c*³ of the frog is provided in its 60 inner face with a longitudinal recess *e*, covered by a metal plate *e*², having a hole *e*³, which corresponds with the recess *e*, and in the plate *e*² and in the part *c*³ of the frog is another hole or recess *e*⁴, adapted to receive a 65 corresponding pin *e*⁵, secured in the part *c*² of the frog. The part *c*² of the frog is also provided with another pin *e*⁶, having a hook-shaped head *e*⁷, which is adapted to be passed through the hole *e*³ in the plate *e*² and into 70 the recess *e*. By means of this construction it will be apparent that the part *c*³ of the frog may be locked to or detached from the part *c*² whenever desired, and the hair *f* is connected with the part *c*³ of the frog in the 75 usual manner and with the staff of the bow at *f*². Whenever it is desired to separate the parts of the bow, the screw *d* is turned, so as to loosen the hair *f*, the frog *c* being moved in the direction of the part *a*⁵ of the staff *a*, 80 and when the frog is moved a sufficient distance to accomplish this result the separate parts of the staff are detached, and the part *c*³ of the frog may also be detached from the part *c*², as will be readily understood. It will 85 also be apparent that the said parts may be again connected whenever desired by reversing this operation, and I thus provide a violin-bow which is composed of different parts easily connected and easily disconnected and 90 which may thus be packed in a small space whenever necessary.

In practice I prefer to wind the sleeve *b* with fine wire, as shown in Fig. 1; but this may or may not be done, and by dividing the staff of the bow at the handle thereof it enables me to make the bow of shorter parts and also make a secure connection, which will not interfere with the operation of the bow in any way.

Having fully described my invention, what I claim as new, and desire to secure by Letters Patent, is—

A violin-bow the staff of which is composed

of two parts detachably connected near the frog thereof, said frog being composed of two parts, the adjacent surfaces of said parts being provided one with longitudinally-arranged recesses and the other with longitudinally-arranged hooks adapted to enter said recesses, the hairs of the bow being also secured to one of said parts of the frog, substantially as shown and described.

In testimony that I claim the foregoing as my invention I have signed my name, in presence of the subscribing witnesses, this 9th day of September, 1902.

MARY E. VERDIER.
